UNITED STATES PATENT OFFICE.

STEPHEN M. HUBBELL, OF CARLAND, MICHIGAN.

BEDSTEAD.

SPECIFICATION forming part of Letters Patent No. 351,055, dated October 19, 1886.

Application filed May 26, 1886. Serial No. 203,301. (No model.)

To all whom it may concern:

Be it known that I, STEPHEN M. HUBBELL, a citizen of the United States, residing at Carland, in the county of Shiawassee and State of Michigan, have invented certain new and useful Improvements in Bedsteads; and I do declare the following to be a full, clear, and exact description of the invention, such as will enable others skilled in the art to which it applies to make and use the same, reference being had to the accompanying drawings, and to letters and figures of reference marked thereon, which form a part of this specification.

This invention relates to bedsteads provided with means for holding bedclothes; and it aims particularly to improve and simplify such means and to devise a construction which shall be compact in arrangement, economical in cost, easy to manage, and durable and efficient in use.

With these ends in view I have devised the simple and novel construction which I will now describe, referring by letter to the annexed drawings, in which—

Figure 1 is a plan view of the foot portion of the bed, showing my improvements in position. Fig. 2 is an inverted plan view. Fig. 3 is a side view with the nearer rail removed. Fig. 4 is an enlarged detail view of the plate in which the fastener-bar is journaled.

The bedstead is of ordinary construction and comprises the foot-board A and side rails, A', provided with the usual slats, A². The fastening device consists of the flat bar B, journaled at one edge in the side rails or plates, C, fastened thereto on the inner sides, a bell-crank lever, D, a hand-lever, E, and notched plate or bar F, and the rod G, connecting the bell-crank and hand-levers.

The fastening-bar B is provided with journals at a distance from its forward edge, which are inserted in one of a series of corresponding openings, c, formed in the sides of the rails, or, better still, the plates C, fastened thereto. By adjusting the bar in any one set of openings the edge may be brought closer to or farther from the foot of the bed, according to the bulk of clothing to be clamped between it and the strip a on the foot-board of the bedstead.

The hand-lever F is pivoted to the under-

side of one of the slats and extends within convenient reach of one side of the bed, and when adjusted to any desired position is held fast by being seated in one of the notches in the bar F. The bell-crank D is secured at one end to the bar, preferably about midway between the ends. The other end extends downward and is connected to the inner end of the hand-lever by the link or bar G.

From the foregoing description and the annexed drawings the operation of the device is readily apparent. By moving the lever E the fastening-bar is turned about its journals, thus varying the distance between its clamping-edge and the foot-board of the bed or the strip thereon. The bedclothes are clamped between the fastening-bar and the foot-board, and are held in place thereby.

Having thus described my invention, what I claim, and desire to secure by Letters Patent, is—

1. The combination, with the bedstead and a strip, of a fastening-bar eccentrically journaled at its ends between the side rails near said strip, and means for actuating said bar to clamp the bedclothes between it and the strip, substantially as and for the purpose described.

2. The combination, with the side rails of a bedstead having a series of corresponding openings on the inner sides, of a fastening-bar journaled between the rails in a corresponding pair of openings, and means for actuating said bar, substantially as and for the purpose described.

3. The combination, with the side rails of a bedstead, of plates having a series of coincident openings fastened to the inner sides of the rails, the clamping-bar journaled between the rails in a corresponding pair of openings in the plates, and means for actuating said bar, substantially as described.

4. In a bedstead, the combination of the fastening-bar journaled between the side rails, a lever depending therefrom, a hand-lever pivoted to one of the slats, a notched bar, and a rod connecting the ends of the two levers, substantially as and for the purpose set forth.

5. In a bedstead, the combination of the foot-board having a strip fastened thereon, a

fastening-bar journaled between the side rails and acting in opposition to the strip, a bell-crank lever depending from the bar, a hand-lever pivoted to one of the slats and extending 5 within convenient reach, a notched bar, and a link connecting the two levers, substantially as shown, and for the purposes described.

In testimony whereof I affix my signature in presence of two witnesses.

STEPHEN M. HUBBELL.
